HAIRPIN

William H. Rothe, Irvington, N. J.

Application August 20, 1945, Serial No. 611,511

2 Claims. (Cl. 132—50)

1

This invention relates to improvements in hairpins for use in dressing the hair and holding it in place, setting pin curls, and for similar purposes; and the invention has reference, more particularly, to a novel hairpin for such purposes which is adapted to clasp the engaged hair and to retain itself in place by its inherent spring characteristics.

The invention has an object to provide a hairpin of such novel construction that, in use, it is adapted to firmly hold in place a given amount of hair without risk of loosening or displacement of the hairpin from the hair, and without risk of injury to either the hair or the user's scalp.

Other objects of this invention, not at this time more particularly enumerated, will be understood from the following detailed description of the same.

The novel hairpin structure according to this invention is shown in the accompanying drawings, in which:

Fig. 1 is a perspective view of the hairpin; Fig. 2 is a side elevational view thereof as lodged in hair to be held in place thereby; and Fig. 3 is a top face view of the same.

Fig. 4 is a side elevational view of the hairpin as used to engage and set a pin curl, the curl being shown in section; and Fig. 5 is a top face view of the hairpin as so applied to a pin curl.

Similar characters of reference are employed in the above described views, to indicate corresponding parts.

The novel hairpin of this invention is formed from a single flat strip of resilient material, such e. g. as spring steel, which is doubled upon itself to provide a bottom section A and an overlying or opposed top section B. Said sections A and B are joined by an end loop 10 of substantial radius, said loop having convergent leg portions 11 and 12 terminating in mutually abutting contact points or stop bends 13 and 14, thus providing a substantially enclosed hair receiving area or space 15 of appreciable capacity within the confines of said loop formation.

Extending from the contact point or stop bend 13, the bottom section A is formed to provide a downwardly bowed arcuate medial hump 16 of substantial longitudinal extent, and, similarly, extending from the contact point or stop bend 14, the top section B is formed to provide an upwardly bowed arcuate medial hump 17 which is opposed to and coextensive with the hump 16 of said bottom section A. Said humps 16 and 17 respectively terminate in mutually abutting contact points or stop bends 18 and 19, thus provid-

ing, between the humps 16 and 17, a substantially enclosed hair receiving area or space 20 substantially equivalent in capacity to that of the hair receiving area or space 15 within the end loop portion of the hairpin.

Extending from the contact point or stop bend 18, the bottom section A is formed to provide an upwardly bowed, shallowly arcuate free end portion 21 of substantial length, the same terminating in an upwardly or outwardly turned end tongue 22, the convex underface of which serves to offset the extremity of the end portion 21 from the user's scalp when inserting the hairpin into the hair and as said hairpin lies in the hair, thus avoiding risk of irritation or injury to the user's scalp.

Extending from the contact point or stop bend 19, the top section B is formed to provide a plurality of keeper humps 23, each comprising an inner relatively long ascending side 24 and an outer relatively short and relatively steeply pitched descending side 25, said descending sides 25 terminating in stop bends 26 adapted to abut the free end portion 21 of the bottom section A, whereby said keeper humps enclose hair receiving spaces 27 of comparatively limited area. By reason of the described formation of said keeper humps 23, the long ascending sides 24 thereof, which are outwardly divergent to the underlying bottom section A of the hairpin, will offer but minimum resistance to the passage of hair between the hairpin sections A and B, when the hairpin is inserted in or applied to the hair by the user, but, once the hair is entered in and confined within the receiving spaces 27 defined by said keeper humps 23, the steeply pitched descending sides 25 of said keeper humps will offer a maximum resistance to outward passage of hair from said spaces 27, and consequently will very effectively obstruct and prevent accidental withdrawing displacement of the hairpin from the hair to which it is applied.

Beyond the outermost keeper hump 23, the top section B terminates in an upwardly inclined terminal portion 28 which is divergent to the free end portion 21 of the bottom section A, and preferably somewhat rearwardly or inwardly offset relative to the extremity of the latter. Said terminal portion 28, as thus related to the bottom section A of the hairpin, may serve as a finger-piece for spreading apart the hairpin sections A and B, when the user applies the hairpin to the hair, and also serves to guide hair into the embrace of said hairpin sections.

55 In the complete hairpin, as comprised by the

structural characteristics above described, the form and positional relation of the parts is such that the hairpin, as a whole, is longitudinally bowed from end to end, so that, when the hairpin is engaged in the hair, some hair will be permitted to underlie the bottom section A with cushioning effect, while at the same time the hairpin will approximately conform to the contour of skull; all whereby the better comfort of the user is assured.

Due to the provision of the relatively large adjoining hair receiving areas or spaces 15 and 20 at the inner part of the hairpin, it will be obvious that the latter is adapted to grasp and, by the spring action of its sections A and B, to clasp a comparatively large amount of hair, whereby to assure firm anchorage of the hairpin in the hair as well as maximum hair embracing and holding effect, while nevertheless the outer parts of the hairpin sections A and B will readily close together, due to their spring tension whereby the same are yieldably urged one toward the other. When the hairpin thus closes, additional minor amounts of hair will be embraced and confined by the keeper humps 23, whereby all tendency of the hairpin to work loose from hair clasping condition is effectively prevented.

Furthermore, due to the provision of the adjoining hair receiving areas or spaces 15 and 20 as separated by the mutually abutting stop bends 13 and 14, the hairpin is admirably adapted to serve as a means for holding and setting pin curls, when the latter are formed in the user's hair. Such use of the hairpin is shown in Figs. 4 and 5, and by reference thereto it will be observed that opposite sides of the pin curl convolutions are respectively embraced and confined in the respective hair receiving areas or spaces 15 and 20, whereby to wind about a center provided by the mutually abutting stop bends 13 and 14, thus not only firmly holding the hair convolutions, but also in a manner to assure a proper shaping and setting of the curl.

Having now described my invention, I claim:

1. A hairpin made of flat spring strip material doubled upon itself to provide opposed bottom and top sections joined by an end loop of substantial radius and substantial length having convergent leg portions terminating in transversely aligned and opposed mutually abutting stop bends, said bottom section having a downwardly bowed arcuate hump of substantial length extending from one said stop bend, said top section having an upwardly bowed arcuate hump of corresponding length extending from the other stop bend and opposed to said hump of the bottom section, said humps respectively terminating in

opposed transversely aligned and mutually abutting additional stop bends, said end loop and opposed humps being adapted to provide enclosed adjoining hair receiving spaces of substantial capacity at the closed end portion of the hairpin, said bottom section terminating beyond its hump in a shallowly curved up-bowed free end portion, and said top section terminating beyond its hump in a transversely corrugate free end portion, the corrugations of which oppose and abut the up-bowed bottom section free end portion whereby to provide a plurality of keeper humps adapted to define and enclose a plurality of additional relatively small hair receiving spaces adjacent the open end portion of the hairpin.

2. A hairpin made of flat spring strip material doubled upon itself to provide opposed bottom and top sections joined by an end loop of substantial radius and substantial length having convergent leg portions terminating in transversely aligned and opposed mutually abutting stop bends, said bottom section having a downwardly bowed arcuate hump of substantial length extending from one said stop bend, said top section having an upwardly bowed arcuate hump of corresponding length extending from the other stop bend and opposed to said hump of the bottom section, said humps respectively terminating in opposed transversely aligned and mutually abutting additional stop bends, said end loop and opposed humps being adapted to provide enclosed adjoining hair receiving spaces of substantial capacity at the closed end portion of the hairpin, said bottom section terminating beyond its hump in a shallowly curved up-bowed free end portion, and said top section terminating beyond its hump in a free end portion provided with a plurality of keeper humps disposed to oppose the up-bowed bottom section free end portion whereby to provide a plurality of keeper humps adapted to define and enclose a plurality of additional relatively small hair receiving spaces adjacent the open end of the hairpin, each said keeper hump comprising an inner relatively long ascending side and an outer relatively short and relatively steeply pitched divergent descending side.
